CLAIM

The ornamental design for a body for a handheld pipette device as shown and described.

DESCRIPTION

FIG. 1 is a front right perspective view of a first embodiment of a body for a handheld pipette device showing it without a pipette attached;

FIG. 2 is a front view of the body for a handheld pipette device shown in FIG. 1;

FIG. 3 is a rear view of the body for a handheld pipette device shown in FIG. 1;

FIG. 4 is a right side view of the body for a handheld pipette device shown in FIG. 1;

FIG. 5 is a left side view of the body for a handheld pipette device shown in FIG. 1;

FIG. 6 is a top view of the body for a handheld pipette device shown in FIG. 1;

FIG. 7 is a bottom view of the body for a handheld pipette device shown in FIG. 1;

FIG. 8 is a front right perspective view of a second embodiment of a body for a handheld pipette device showing it without a pipette attached;

FIG. 9 is a front view of the body for a handheld pipette device shown in FIG. 8;

FIG. 10 is a rear view of the body for a handheld pipette device shown in FIG. 8;

FIG. 11 is a right side view of the body for a handheld pipette device shown in FIG. 8;

FIG. 12 is a left side view of the body for a handheld pipette device shown in FIG. 8;

FIG. 13 is a top view of the body for a handheld pipette device shown in FIG. 8;

FIG. 14 is a bottom view of the body for a handheld pipette device shown in FIG. 8;

FIG. 15 is a front right perspective view of a body for a handheld pipette device of FIG. 1 showing it with a pipette attached;

(Continued)

FIG. 16 is a front view of the body for a handheld pipette device shown in FIG. 15;
 FIG. 17 is a rear view of the body for a handheld pipette device shown in FIG. 15;
 FIG. 18 is a right side view of the body for a handheld pipette device shown in FIG. 15;
 FIG. 19 is a left side view of the body for a handheld pipette device shown in FIG. 15;
 FIG. 20 is a top view of the body for a handheld pipette device shown in FIG. 15;
 FIG. 21 is a bottom view of the body for a handheld pipette device shown in FIG. 15;
 FIG. 22 is a front right perspective view of a body for a handheld pipette device of FIG. 8 showing it with a pipette attached;
 FIG. 23 is a front view of the body for a handheld pipette device shown in FIG. 22;
 FIG. 24 is a rear view of the body for a handheld pipette device shown in FIG. 22;
 FIG. 25 is a right side view of the body for a handheld pipette device shown in FIG. 22;
 FIG. 26 is a left side view of the body for a handheld pipette device shown in FIG. 22;
 FIG. 27 is a top view of the body for a handheld pipette device shown in FIG. 22; and,
 FIG. 28 is a bottom view of the body for a handheld pipette device shown in FIG. 22.
 The dashed lines shown in FIGS. 15-28 in form of a pipette on the bottom, depict environmental subject matter and form no part of the claimed design. The remaining dashed lines in the drawings depict portions of the body for a handheld pipette device that form no part of the claimed design.
